(57) **CLAIM**

The ornamental design for a billiard cue, as shown and described.

DESCRIPTION

The article is a billiard cue.

FIG. 1 is a right side view of a billiard cue design.

FIG. 2 is a top view thereof.

FIG. 3 is a left side view thereof.

FIG. 4 is a bottom view thereof.

FIG. 5 is a reduced top view thereof, the broken line showing of the forward portion of the billiard cue is for illustrative purposes only and forms no part of the claimed design; and,

FIG. 6 is a rear end view of FIG. 1.
